UNITED STATES PATENT OFFICE.

JAMES A. CHARNLEY, OF PROVIDENCE, RHODE ISLAND.

DESIGN FOR A PAPER COLLAR.

Specification forming part of Design No. 2,498, dated October 30, 1866.

To all whom it may concern:

Be it known that I, JAMES A. CHARNLEY, of Providence, in the county of Providence and State of Rhode Island, have invented a new and Improved Design for Paper Collars or other Materials; and I do hereby declare that the following is a full, clear, and exact description thereof, which will enable others skilled in the art to make and use the same, reference being had to the accompanying drawing, forming part of this specification.

The drawing represents a front elevation of this invention.

The principal features of this design are embossed sharp points and embossed round points or scallops, whereby the appearance of the article is materially improved and an elegant collar or other article is obtained.

A represents a strip of paper or other suitable material, which is made in any desirable width and length and provided on its edges with embossed sharp points *a* and with embossed round points or scallops *b*, as shown. By these points and scallops a new and elegant appearance is given to the collar.

Having thus described my invention, I claim as new and desire to secure by Letters Patent-- The design for a paper collar, as shown and described.

The above specification of my invention signed by me this 10th day of September, 1866.

JAMES A. CHARNLEY.
